TOY LIVESTOCK TRAILER

Allan J. Alvaney, Arlington Heights, Ill., assignor to Sears, Roebuck and Co., Chicago, Ill., a corporation of New York

Filed Sept. 16, 1960, Ser. No. 62,176

Term of patent 7 years

(Cl. D34—15)

Fig. 1

Fig. 2

FIG. 1 is a perspective view of a toy livestock trailer embodying my new design, showing top, front and side thereof, and

FIG. 2 is a rear elevation of same.

The side opposite that shown in FIG. 1 is similar to the side shown, and the bottom is plain.

The essential features of my design reside in the portions shown in full lines.

I claim:

The ornamental design for a toy livestock trailer, substantially as shown and described.
